(57) **CLAIM**

The ornamental design for a nozzle for soldering iron, as shown and described.

DESCRIPTION

FIG. 1 is a perspective view of a nozzle for soldering iron; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view taken along line 8-8 in FIG. 4 thereof.

The broken lines in the drawings depict unclaimed environmental subject matter.

The dashed lines show a boundary between the claimed design and unclaimed portions.
